The ornamental design for a bottle, as shown and described.

DESCRIPTION

FIG. 1 is a top, front, right perspective view of embodiment one, of a bottle, showing our new design;

FIG. 2 is a front view thereof;

FIG. 3 is a right side view thereof;

FIG. 4 is a rear view thereof;

FIG. 5 is a left side view thereof; and,

FIG. 6 is a top view thereof; and,
FIG. 7 is a top, front, right perspective view of embodiment two, of a bottle, showing our new design.

The broken line leaf portions of FIGS. 1-6 show unclaimed subject matter only and form no part of the claimed design. None of the broken lines form a part of the claimed design.
